(57) **CLAIM**

The ornamental design for a set of swageless invisible tension, as shown and described.

DESCRIPTION

FIG. 1 is a perspective view of a set of swageless invisible tension showing my new design;

FIG. 2 is a perspective view of a fixing part of the set of swageless invisible tension;

FIG. 3 is a front view thereof;

FIG. 4 is a rear view thereof;

FIG. 5 is a right side view thereof;

FIG. 6 is a left side view thereof;

FIG. 7 is a top view thereof, a bottom view being flat and devoid of surface ornamentation;

FIG. 8 is a perspective view of a tensioning part of the set of swageless invisible tension;

FIG. 9 is a rear view thereof;

FIG. 10 is a front view thereof;

FIG. 11 is a right side view thereof;

FIG. 12 is a left side view thereof;

FIG. 13 is a top view thereof; and,

FIG. 14 is a bottom view thereof.

The broken lines depict portions of the set of swageless invisible tension in which the design is embodied that form no part of the claimed design.
